UNITED STATES PATENT OFFICE.

WALTER F. BLAKE, OF CHICAGO, ILLINOIS, AND LEWIS C. HUNTER, OF FORT WAYNE,
INDIANA.

MANIFOLDING RECEIPT.

No. 883,079.

Specification of Letters Patent. Patented March 24, 1908.

Application filed February 18, 1907. Serial No. 357,789.

To all whom it may concern:

Be it known that we, WALTER F. BLAKE and LEWIS C. HUNTER, citizens of the United States, and residents, respectively, of Chicago, Illinois, and Fort Wayne, Indiana, have invented certain new and useful Improvements in Manifolding Receipts, of which the following, taken in connection with the drawing, is a specification.

Our invention has for its object the production of a triplicate receipt by means of which three copies may be made at one writing without the use of separate carbon sheets, and is designed to be used more particularly by railroads and like companies where it is desirable to have at least three copies of each receipt or other document. These receipts are so folded together and bound as to form a book containing any number of receipts desired, the same being secured together, preferably at the end thereof, with an adjustable fastening, by means of which after any number of receipts have been torn out, the fasteners may be readily and easily tightened and the remaining receipts held in place until used.

Other novel features and advantages of construction will be hereinafter more fully described and pointed out in the claims.

In the accompanying drawings forming part of this specification, and in which like letters of reference indicate corresponding parts, we have illustrated what we now consider the preferred form of construction and in these drawings

Figure 1 is a perspective view of a book of triplicate receipts, ready for use; Fig. 2 is a perspective view of one set of receipts after being torn from the book, showing the copying preparation on the back of the first leaf; Fig. 3 is a fragmentary detail with the cover removed showing the fastening device after part of the receipts have been torn out, before adjusting to clamp the remaining receipts; Fig. 4 is a fragmentary view of one set of receipts illustrating one of the filing apertures and one of the slots for the fastening device.

In carrying out our invention a , a' , a'' indicate the triplicate receipts, sections a and a' of said receipts being provided upon the back thereof with a coating of copying preparation, so that as the sections are folded together, the copying preparation upon the back of section a reproduces the copy upon section a' and the copying preparation upon the back of section a' reproduces a copy upon section a'' .

One edge of each section a' and a'' is provided with perforations b , b' arranged in proper position for filing after the receipts have been filled out and used, at the same edge and upon either side of the perforations b , b' are small slots c , c' extending longitudinally of the section of paper a' , a'' through which the fastening devices are extended.

The fastening devices used in binding the sheets together are preferably of the kind provided with a head d and double shank portions d' which are passed through the slots c , c' and the ends thereof bent in opposite directions as shown in Figs. 1 and 3 to hold the different sections together.

e is a backing or cover having one end thereof bent around and bound with the sheets, and being of sufficient length to overlap and fold back under the first set of receipts a , a' , a'' as shown in Fig. 1. When the user is about to make out a receipt he places the loose end e' of the backing, beneath the top set of triplicate receipts, so as to prevent any impressions of the writing from appearing on any of the sheets below the first set.

After a receipt has been filled out the user simply pulls it from its place, the slot c , c' tearing straight to the edge of the paper as shown in Fig. 2, after which the receipts are separated along the line of perforations b , b' .

When any number of receipts have been used and torn out the fastening devices may be readily and easily adjusted to retain the remaining sheets in position, by pressing the binding e down and spreading the shanks of the fastening devices. The advantages of this method will be apparent, and while we have described our device as being applied

particularly to railroad receipts it is obvious that it may be used in making duplicates of other documents.

We claim:—

- 5 A loose leaf manifolding book, comprising a plurality of sheets of paper each of which is perforated transversely and folded to form triplicate slips, manifold material upon one side of two of said slips, a cover having one end thereof adapted to be folded under the slips being written upon, and means for binding the folded sheets and cover together

at one end thereof, said binding means being adapted for tightening adjustment as the slips are torn from the book.

WALTER F. BLAKE.
LEWIS C. HUNTER.
